(57) **CLAIM**

The ornamental design of a spindle, as shown and described.

DESCRIPTION

The disclosed spindle may be used in decking and/or other applications.

The FIGURE is a front view of the spindle of the present invention, the rear view, the right side view, and the left side view being identical to the front view.

The top and bottom of the spindle of FIG. 1 form no part of the claimed design.

1 Claim, 1 Drawing Sheet

The Figure
